UNITED STATES PATENT OFFICE.

FREDERICK N. CONNET, OF PROVIDENCE, RHODE ISLAND.

GRINDING-MACHINE.

No. 926,101.

Specification of Letters Patent.

Patented June 29, 1909.

Application filed November 28, 1907. Serial No. 403,482.

To all whom it may concern:

Be it known that I, FREDERICK N. CONNET, a citizen of the United States, residing at the city of Providence, in the county of Providence and State of Rhode Island, have invented certain new and useful Improvements in Grinding-Machines, of which the following is a specification, reference being had therein to the accompanying drawings.

10 This invention relates to grinding machines, and has for its object to provide a grinder of simple and practical construction which is more particularly adapted and designed to expedite the grinding of surfaces, 15 the machine being so arranged that work may be simply laid upon its table and then pushed through the machine by hand, so that the grinder will quickly act upon the lower surface of the work.

20 The essential feature of the invention is that the grinding ring is supported below the table so that its upper edge is flush with or extends slightly above the surface of said table.

25 Another essential feature of the construction is that a rest or support composed of a center table piece is located inside of the grinding ring leaving only a narrow slot or channel through which the working surface 30 of the ring projects, by which construction the work is never without a guide and support as it is passed through the machine over the grinding ring.

With these and other objects in view, the 35 invention consists of certain novel features of construction, as will be more fully described and particularly pointed out in the appended claims.

In the accompanying drawings: Figure 40 1—is a top view of my improved machine showing the location of the grinding ring in the table of the machine. Fig. 2—is a sectional side elevation of the machine on line 2—2 of Fig. 1. Fig. 3—is a central end 45 elevation, partly in section. Fig. 4—is a section on line 4—4 of Fig. 1. Fig. 5—is a perspective view showing the side guides and center supporting plate. Fig. 6—shows a portion of a top view of the grinding ring 50 and spring sections and binding ring, by which the grinder is bound and held in position. Fig. 7—is an enlarged sectional detail showing the binding ring acting on the sections to hold the grinding ring in position. Fig. 8—is a detail side elevation of the clamping member.

Referring to the drawings, at 1 is the main frame of the machine made preferably in the form of a box, and supported on the base 2. The bottom plate 2^a of the frame 60 is provided with an inwardly projecting hollow boss 3. A short distance down from the upper edge of this frame is located a bearing 4 which is supported by a web or the ribs 5—5. At 6 is an upright shaft supported at its upper end in the bearing 4. The lower end of this shaft rests in the cup-shaped bearing 7, which bearing is threaded at 8 at its upper end and adapted to be adjusted vertically by means of the nut 9 70 which rests on the top of the boss 3. This vertically adjustable bearing is prevented from turning by the set-screw 10 which enters the groove 11 in the side thereof. The upper end of this shaft is supplied with 75 a bearing collar 12 to which is bolted the bowl-shaped clamping member 13. The upper edge of this member is provided with the rim 14 which is sawed into or split at intervals all around its periphery, thereby 80 providing a plurality of semi-flexible sections. The outer edge of this rim around these sections is beveled as at 15, see Figs. 7 and 8, and adapted to receive the binding ring 16 which is correspondingly beveled on 85 its interior surface and is adapted to surround these fingers whereby when the tension bolts 17—17, which are distributed around the ring, are set up said fingers are 90 sprung inward to grip and retain the grinding ring 18 which is located within. In order to provide a vertical adjustment for 95 this grinding ring I have constructed an inner plate 19, on which the ring sets, said plate being threaded onto the inwardly projecting hub 20 of the clamping member 13. Supporting tables 21 and 22 may be bolted at 23 and 24 on either side of this frame, which tables may be vertically adjustable, if desired, by means of the set-screws 25 and 100 26 located at their lower ends. The inner edges 27 and 28 of these tables project inward close to the outer edge of the grinding ring 18 and are shaped to conform to the circle of said ring so as to set close up to 105 the same. Two guide plates 29 and 30 extend along on either side of these adjustable tables and over the edge of the grinding ring, said plates being supported on the upper edge 31 of the main frame 1, and secured in position by means of the bolts 32— 110 32. These two guide plates are connected to

gether by means of a center circular table 33 which they are arranged to support, said table being adapted to set down into the center of the grinding ring. This center table may 5 be raised and lowered by a vertical adjustment of the guide plates 29 and 30 which may be accomplished by moving the wedges 34 and 35, (see Figs. 3 and 4), which are arranged under the edges of said plates 10 either in or out, or this adjustment may be accomplished by any other convenient means. The circular grinding ring is driven through the shaft 6 and pulley 36 by means of the driving belt 37 which leads over the idler 15 pulley 38.

An exhaust pipe 39 may extend through the side of the machine, as shown in Fig. 3, which may be connected to an exhaust fan, not shown, for removing the waste material. 20 This machine is particularly adapted for quickly surfacing rough castings, or other work, which may be passed through the machine by hand.

In operating the machine, the table 21 is 25 usually made slightly lower than the upper edge of the grinding ring. The center table and table at the opposite end of the machine are usually made about flush with the top edge of the grinder so that practically all of 30 the work is done by the edge of the ring at the entering end of the machine, but the tables at either side may be adjusted to any height desired so that work may be entered from either side. It will be seen by this construction 35 that the work is guided on both edges while being passed through the machine, and that the work is also supported on its under-side by both the end tables and the center table while being passed across the 40 face of the ring, the working surface of which merely extends through a slot or channel made to receive it. Another feature of this construction is that small work, or articles, may be clamped to a yoke and brought into 45 contact with the surface of the grinding ring by sliding said yoke across the surface of the guide plates 29 and 30.

Instead of supporting the device directly from the floor in an upright position, in the 50 manner shown, the whole device may, if desired, be turned up-side-down and supported from above whereby the work may be pressed against the face of the grinder from beneath the tables. Or if desired the machine 55 may be turned up on its side and the work passed along in front of it and pressed

against its face. In other words, I do not wish to be restricted to working the whole machine in any particular position but only to confine myself to the relative position of 60 the different parts.

The machine is very simple and practical in its construction, effective in its operation, and by its arrangement grinding the faces of castings or the like is greatly facilitated. 65

Having thus described my invention, what I claim as new and desire to secure by Letters Patent, is:

1. A grinding machine comprising a 70 grinding ring, means for rotating said ring, a table for guiding the work to the ring, a table for guiding the work from the ring, a work supporting table in the center of said ring, and means for adjusting said center table independent of said ring and said guiding tables.

2. A grinding machine comprising a 75 grinding ring, a supporting table for guiding the work to said ring, a table in the center of said ring for receiving and supporting the work, a supporting table for guiding the work from said ring, means for adjusting the tables with relation to the ring, and means for rotating said ring.

3. A grinding machine comprising a 80 grinding ring, a work supporting table for guiding the work to said ring, said ring being supported beneath the face of said table whereby its upper edge may engage the work, a work supporting table in the center 85 of said ring, guide plates connected to said center table for supporting the same, means for vertically adjusting said guide plates, and means for rotating said ring.

4. A grinding machine comprising a 90 grinding ring, a work supporting table on either side of said ring, said ring being supported below said table whereby its upper edge may engage the work, a work supporting table in the center of said ring, guide 95 plates connected to said center table for supporting the same, means for vertically adjusting both the side and the center tables 100 with relation to the ring, and means for rotating said ring.

In testimony whereof I affix my signature in presence of two witnesses.

FREDERICK N. CONNET.
